WILLIAM S. BACON, OF SAN DIEGO, CALIFORNIA, ASSIGNOR OF ONE-HALF TO OTTO KESSLER, OF SAN DIEGO, CALIFORNIA.

SWIVEL CONNECTION FOR ELECTRIC CONDUCTORS.

1,174,379.

Specification of Letters Patent.

Patented Mar. 7, 1916.

Application filed April 10, 1915. Serial No. 20,420.

To all whom it may concern:

Be it known that I, WILLIAM S. BACON, a citizen of the United States, residing at San Diego, in the county of San Diego and

5 State of California, have invented new and useful Improvements in Swivel Connections for Electric Conductors, of which the following is a specification.

This invention relates to swivel connections for electric conductors, and more particularly to such conductors as are ordinarily used for electric lighting and telephone connections, etc.

The prime object of this invention is the 15 provision of a means, embodying a swivel joint, which may be interposed upon a wire or series of wires at any convenient point between an immovable end and a movable end, so as to prevent twisting and kinking 20 of such wires, when being moved about. For instance, on a telephone of the desk type, the wiring connections between the bell box and the transmitter-stand very often become twisted and kinked from constant 25 use and moving of the transmitter-stand, thereby greatly shortening the life of the wires. Furthermore such kinking of the wire connections prevents the stand from being transported to the limit of the full 30 and normal length of the cord.

The device comprises members swivelly connected together and provided with means whereby electrical energy is uninterruptedly transmitted therethrough, and constructed 35 in such a manner as to insure perfect electrical contact, ease of operation, and adequate insulation.

The construction and operation of the device will be more clearly set forth in the 40 following specification, reference being had to the accompanying drawings, in which:

Figure 1 is a view in side elevation showing the application of the device to a typical business telephone, of the desk type. Fig. 45 2 is a view in vertical section through the center of the device. Fig. 3 is a view in transverse section, as seen on the line 3—3 of Fig. 2. Fig. 4 is a view in transverse section, as seen on line 4—4 of Fig. 2. Fig. 50 5 is a similar view taken as indicated by line 5—5 of Fig. 2. Fig. 6 is a detailed perspective view of a typical contact ring, with an electric conductor formed integral therewith. Fig. 7 is a similar view illustrating a spring washer which holds the 55

rings in contact. Fig. 8 is a detailed perspective view of a modified spring washer with the electric conductor formed integral therewith. Fig. 9 is a detailed perspective view of a contact ring used in connection with the spring washer shown in Fig. 8.

My device consists of a pair of insulating core members 11 and 12. For the purpose of this description it will be assumed that core member 12 is stationary and core member 11 is mounted rotatable in relation thereto but it is obvious that member 11 may be regarded as stationary and member 12 as rotatable. The core members are of cylindrical shape and the stationary member 70 is provided at its upper end with an upstanding flange 25. The rotatable member 11 has the end engaging the stationary member cut away, as at 26, forming a circular shoulder adapted to engage flange 25. The 75 reduced end formed by said cut away portion is of lesser height than the height of flange 25 thereby forming a cylindrical chamber 27 between the two core members. An insulating disk 28 of slightly smaller 80 dimension than the cylindrical chamber 27 is disposed therein. Said disk is provided with a plurality of bores 15 arranged in a series of concentric circles whose center is the center of said disk. Mounted in said 85 bores, and freely rotatable therein, are ball bearings 15 of slightly greater diameter than the thickness of the disk, whereby said ball bearings will extend slightly above the sides of the disk. The core members 11 and 12 90 are provided with circular channels 29 which are opposite the concentric circles in which the ball-bearings 15 are mounted. Contact rings 18 are disposed in said channels 29 on opposite sides of the rings. In order to assure a perfect contact the face of the rings engaging the ball bearings is grooved 95 conforming to the curvature of the ball bearings extending above the surface of the disk. Each of said rings is formed integral with 100 an electric conductor 30 passing parallel to the longitudinal axis of said core members. In order to insure perfect contact between the contact rings and the ball bearings, a split ring washer 40 is provided for each 105 contact ring disposed between the core member and said ring, the conductor of each ring being disposed in the slot of the spring washer holding the latter against rotation.

In Fig. 8 I have shown the electric con- 110

ductor as formed integral with the spring washer 40 instead of the contact ring. Passing through the central longitudinal axis of the core members and also through the center of the disk, is a post or rod 13. This rod is provided at one end with a head 41 and at the other with a nut 42 on its threaded end whereby the core members may be securely bolted together.

10 I have shown a swivel connection for three electric conductors, the central rod 13 acting as one of said conductors. In order to allow for the rotation of the wire fixture connected to said stationary central rod 13, 15 I provide a flat arm 32 pivoted to rod 13 at one end and secured to the wire fixture at the other, whereby on the rotation of core member 11 the wire fixture connected to central rod 13 may freely rotate about said 20 rod. It is obvious that central rod 13 need not be used as an electric conductor and only the conductors making contact with the ball bearings may be used. It is also obvious that the number of conductors and the corresponding 25 contact rings and series of ball bearings may be increased to correspond to the number of electric conductors which it is desired to connect. The terminals 33 of the conductors extending beyond the body of the core members serve also as binding posts for the wire fixtures. A semi-cylindrical cap 34 covering said binding posts and ends of conductors is secured to each end of the core members, and is provided at its apex 30 with an insulating ring 35 through which the central cord 36 containing the electric conductors passes.

From the foregoing description the operation of my swivel connection will be easily 40 understood. The electric currents passing through the conductor of one core member to the contact rings which are also electric conductors, will pass through ball bearings 45 which serve the double function of conductors and anti-friction bearings to the contact rings on the opposite side of said ball bearings, and from said rings the current passes through the conductors of the other core member. Since the contact rings 50 are always in touch with the ball bearings it will be seen that an electric conductor is established between the conductor of one core member and the conductor of the other core member irrespective of the position of 55 the rotatable core member to the stationary one.

Changes in the construction of my device, without departing from the spirit of my invention and within the scope of the appended claims, will occur to those skilled in the art.

I claim:

1. A swivel connection for electric conductors comprising a pair of cylindrical insulating cores, one of said cores having an

upwardly extending flange on its upper periphery, the other of said cores having a circular shoulder adapted to fit and engage said flange, one of said cores having a cylindrical recess at one end and forming a closed 70 chamber with the end of the other core, a circular insulating disk in said chamber, said disk being provided with cylindrical bores, said bores being arranged in a plurality of concentric circles, ball bearings 75 of slightly greater diameter than the thickness of said disk mounted in said bores so as to be freely rotatable therein, a pair of contact rings on opposite sides of each circle of bores, said contact rings and said ball 80 bearings being electric conductors, a spring washer disposed between the core body and each ring and adapted to force said rings with yielding pressure against said ball bearings, separate electric conductors passing through each of said cores and each connected with one of said rings, a stationary conductor rod passing through the central longitudinal axis of said core members and through the center of said disk, holding 85 said cores together and allowing rotary movement of one core in relation to the other, an arm pivotally connected with said stationary conductor rod and secured to a wire conductor, and a pair of caps covering 90 the outer ends of the core members.

2. A swivel connection for electric conductors comprising a pair of pivotally connected insulating cores, one of said cores having a recess at one of its ends and forming a closed chamber with the end of the other core, a circular insulating disk rotatably mounted in said chamber, said disk being provided with bores, said bores being arranged in a plurality of concentric circles, ball bearings of slightly greater diameter than the thickness of the disk mounted in said bores and freely rotatable therein, contact rings interposed between said cores and said ball bearings on opposite sides of said disk, each of said contact rings being adapted to engage one series of circularly arranged ball bearings and being grooved on its ball bearing engaging face, said contact rings and said ball bearings being electric 100 conductors, springs for holding said rings against said ball bearings with yielding pressure, separate electric conductors passing through the longitudinal axis of said cores, each of said conductors being connected with one of said rings, wire fixtures connected to the terminals of said conductors at the outer ends of said cores, and caps inclosing the outer ends of said cores, a rod 105 on which said cores are mounted for relative rotary movement, said rod passing through the central longitudinal axis of said cores and through the center of said disk.

3. A swivel connection for electric conductors comprising a pair of insulating 110

- cores, one of said cores having a recess at one of its ends and forming a closed chamber with the end of the other core, a circular insulating disk rotatably mounted in said chamber, said disk being provided with bores, said bores being arranged in a plurality of concentric circles, ball bearings of slightly greater diameter than the thickness of the disk mounted in said bores and freely rotatable therein, contact rings interposed between said cores and said ball bearings on opposite sides of said disk, each of said contact rings being adapted to engage the projecting portion of one series of the 5 circularly arranged ball bearings, said contact rings and said ball bearings being electric conductors, springs for holding said rings against said ball bearings with yielding pressure, separate electric conductors 10 passing through said cores, each of said conductors being electrically connected with one of said rings, wire fixtures connected to the terminals of said conductors at the outer ends of said cores, a rod on which said cores 15 are mounted for relative rotary movement, said rod passing through the longitudinal axis of said cores and through the center of said disk.
4. A swivel connection for electric conductors comprising a pair of insulating cores, one of said cores having a recess at one of its ends and forming a closed chamber with the end of the other core, a circular insulating disk mounted in said chamber, 20 said disk being provided with bores, said bores being arranged in a plurality of concentric circles, ball bearings mounted in said bores and freely rotatable therein, contact rings interposed between said cores and said 25 ball bearings on opposite sides of said disk, each of said contact rings being adapted to engage the upper part of one series of circularly arranged ball bearings, said contact rings and said ball bearings being electric conductors, 30 springs for holding said rings against said ball bearings with yielding pressure, separate electric conductors passing through said cores, each of said conductors being electrically connected with one of said rings, wire fixtures connected to the terminals of said conductors at the outer ends of said cores, a rod on which said cores 35 are mounted for relative rotary movement, said rod passing through the longitudinal axis of said cores and through the center of said disk.
4. A swivel connection for electric conductors comprising a pair of insulating cores, one of said cores having a recess at one of its ends and forming a closed chamber with the end of the other core, a circular insulating disk mounted in said chamber, 40 said disk being provided with bores, said bores being arranged in a plurality of concentric circles, ball bearings mounted in said bores and freely rotatable therein, contact rings interposed between said cores and said 45 ball bearings on opposite sides of said disk, each of said contact rings being adapted to engage the upper part of one series of circularly arranged ball bearings, said contact rings and said ball bearings being electric conductors, 50 springs holding said rings against said ball bearings with yielding pressure, separate electric conductors passing through said cores, each of said conductors being connected with one of said rings, wire fixtures connected to the terminals of said conductors at the outer ends of said cores, a rod on which said cores 55 are mounted for relative rotary movement, said rod passing through the central longitudinal axis of said cores and through the center of said disk.
5. A swivel connection for electric conductors comprising a pair of insulating cores, one of said cores having a recess at one of its ends and forming a closed chamber with the end of the other core, an insulating disk mounted in said chamber, said disk being provided with bores, said bores being arranged in a plurality of concentric circles, 60 ball bearings mounted in said bores and freely rotatable therein, contact rings interposed between said cores and said ball bearings on opposite sides of said disk, each of said contact rings being adapted to engage the upper part of one series of circularly arranged ball bearings, said contact rings and said ball bearings being electric conductors, 65 springs for holding said rings against said ball bearings with yielding pressure, separate electric conductors passing through said cores, each of said conductors being electrically connected with one of said rings, wire fixtures connected to the terminals of said conductors at the outer ends of said cores, a rod on which said cores 70 are mounted for relative rotary movement, said rod passing through the central longitudinal axis of said cores and through the center of said disk, holding said cores together and allowing rotary movement of one core in relation to the other.
6. A swivel connection for electric conductors comprising a pair of insulating cores, one of said cores being provided with a disk chamber, an insulating disk mounted therein, said disk being provided with a plurality of sets of electric conductors, said sets 75 of conductors being arranged in concentric circles, contact rings interposed between said cores and said conductors on opposite sides of said disk, said contact rings engaging said electric conductors, separate electric conductors passing through said cores, each of said last-named conductors being electrically connected with one of said rings, wire fixtures connected to the terminals of said last-named conductors, and means pivotally connecting said cores and allowing rotary movement of one core in relation to the other, the axis of rotation passing through the center 80 of said concentric circles.
7. A swivel connection for electric conductors comprising a pair of insulating cores disposed end to end, an insulating disk mounted therebetween, said disk being provided with a plurality of sets of electric conductors, said sets of conductors being arranged in concentric circles, contact rings interposed on opposite sides of said disk between said cores and said conductors and engaging the latter, separate electric conductors passing through said cores, each of said last-named conductors being electrically connected with one of said rings, wire fixtures connected to the terminals of said last-named conductors, and means connecting said cores and allowing rotary movement in 85 relation to each other.
8. A swivel connection for electric conductors comprising a pair of insulating cores disposed end to end, an insulating disk mounted therebetween, said disk being provided with a plurality of electric conductors arranged in a circle, contact rings on opposite sides of said disk, said rings being interposed between said cores and said conductors and electrically connected with the 90

latter, separate electric conductors passing through said cores, each of said last-named conductors being connected with one of said rings, wire fixtures connected to the terminals of said last-named conductors, a stationary conductor rod passing through the central longitudinal axis of said core members and through the center of said disk, said rod holding said cores together and allowing rotary movement of one core in rela-

tion to the other, and an arm pivotally connected with said rod and secured to an electric conductor.

In witness that I claim the foregoing I have hereunto subscribed my name this 13th day of March, 1915.

WILLIAM S. BACON.
